UNITED STATES PATENT OFFICE.

JACOB W. CAMPBELL, OF WENDEL, PENNSYLVANIA.

MINE DRILL.

Application filed January 12, 1923. Serial No. 612,235.

To all whom it may concern:

Be it known that I, JACOB W. CAMPBELL, residing at Wendel, in the county of Westmoreland and State of Pennsylvania, a citizen of the United States, have invented or discovered certain new and useful Improvements in Mine Drills, of which improvement the following is a specification.

My invention relates to the construction 10 of mine drills and, specifically, to a drill which, being mounted for example on a coal-mining machine, may be employed for drilling blast holes in the breast of coal opposite which the mining machine is 15 brought, and which the mining machine itself is adapted to undercut.

In the accompanying drawings I show the 20 drill mechanism in which my invention consists. In these drawings Figure I is a view in plan from above of the apparatus; Fig. II is a view of it in side elevation, Figure III is a view in transverse vertical section, on the plane indicated at III—III, Fig. I; Figure IV is a similar view on a 25 plane indicated at IV—IV, Fig. I; Figure V is a view similar to Fig. I, illustrating a modification.

Describing first the machine as it is shown in Figs. I to IV, inclusive, the bed plate is 30 indicated by the reference numeral 1. The machine may upon this bed plate be mounted wherever desired, but as I have already intimated, it ordinarily will be mounted upon the deck of a coal-mining machine. I 35 have not in the drawings shown the coal-mining machine, with my drilling apparatus applied to it, but the arrangement will be understood from what I have said without any such additional showing.

Upon the bed plate 1 of the machine a frame 2 is pivoted at 3. This frame is elongate for purposes presently to be described. The frame may be swung on its pivot 3 and raised and lowered to direct the 40 drill which extends longitudinally from and beyond the end of the frame at any angle which may be desired. Racks and pinions 4 and 5 are provided, the racks pivoted to the bed plate 1, the pinions rotatable in the 45 frame 2, and by means of the racks and pinions the frame may be swung on its pivot. The pinions 5 are turned by the hand crank 6. More minutely, a pair of plates 30 rigidly mounted on frame 2 afford opposite 50 bearings for the shaft which constitutes the common axle of the two pinions 5. These

plates 30, additionally, carry pivoted to them, keepers 20, and through keepers 20 the racks 4 extend. In operation the keepers turn slightly on their pivots as the frame 60 swings on its pivot 3, and they are effective to hold the racks to engagement with the pinions.

A pair of screws 21 extend longitudinally of the frame and a carriage 14 threaded 65 upon the screws is by the turning of the screws movable longitudinally of the frame.

A drill shaft 8 is rotatably mounted in carriage 14, and protrudes beyond the end of frame 2. As the carriage 14 moves along 70 the frame 2 the extent to which the drill shaft 8 protrudes will vary. The drill shaft 8 carries at its outer end the drill 7. At its inner end, and within frame 14, the drill shaft 8 is provided with a pinion 10, 75 and this pinion 10 meshes with a second pinion 11, also mounted in carriage 14.

A counter shaft 9 extends longitudinally of frame 2. It passes through carriage 14, and pinion 11 is splined upon it, so that pinion 11 may range longitudinally along shaft 9, and at the same time rotation of shaft 9 will effect rotation of pinion 11, and consequent rotation of pinion 10 and shaft 8 and drill 7. 85

The shaft 9 is driven from a power shaft 12 through the bevel gearing 16, 17. The bevel gear 17 is, through the manually controlled clutch 13, capable of being integrated with the shaft 18 rotatably mounted on bed 90 plate 1, and shaft 18 and shaft 9 are articulated together by the universal joint 19. This universal joint is aligned with the pivots 3, and is effective to rotate the drill while frame 2 swings on the pivots 3. 95

The screws 21 are rotated by manually driven worm drive. The crank arm of this worm drive is indicated at 15, and it will be understood that the turning of the crank will cause the turning of worms 23 which 100 engage the worm pinions 22 with which the screws 21 are equipped.

So long as power is applied and shaft 12 is rotated the drill 7 may be set into rotation merely by the shifting and closing of 105 the clutch 13, and, the clutch 13 being closed, and the shaft 12 rotated, the drill 7 will continue to rotate, whatever be the position of the frame. The attendant has at his hand two cranks 6 and 15 and, by turning one of 110 them and the other, the frame may be swung so as to direct the drill at the desired angle.

and the carriage 14 may be advanced so as to cause the drill to engage and sink into the breast of coal or other body into which a hole is to be drilled.

- 5 5. The advantage of having manually operated elevating apparatus is that the attendant has the directing of the drill under his easy immediate control, and the advantage of having the forward feed of the drill under 10 manual control is that when in the course of drilling the instrument strikes a harder body, the attendant, perceiving it, may adapt operation to the changed condition. It is common in drilling apparatus in which the 15 drill is advanced under mechanical power for drills to be broken when they encounter such hard bodies.

The machine of Figure V requires no more than a few words of further explanation. 20 20. In this case the screws 21 are omitted, and instead endless ropes 25 engage the carriage 14, and these endless ropes being wrapped about a drum 26, are driven by the rotation of the drum to effect the shifting 25 of the carriage, and the drum is rotated by the crank arm 15 precisely as, in the machine of Figs. I to IV, the worm drive is effected by crank arm 15.

I claim as my invention:

- 30 30. 1. In a drilling machine the combination of a bed plate, a frame pivoted to the bed plate, a shaft formed in two parts united by universal joint on the axis of the frame pivot and carried, the one part by the bed plate the other by the frame, a drill borne by a shaft and extensible from said frame, said drill shaft and the shaft first named being geared together, means for rotating the shaft first named, manually operated means 35 for swinging the frame on its pivot, and

manually operated means for effecting extension of said drill shaft from said frame.

2. In a drilling machine the combination of a bed plate, a frame pivoted to said bed plate, manually operated means for causing 45 the frame to swing on its pivot, a carriage movable longitudinally of said frame, manually operated means for effecting movement of said carriage along said frame, a rotatable shaft borne by said frame and 50 articulated to the shaft borne by the bed plate in a joint coaxial with the frame pivot, a rotatable drill shaft borne by said carriage and throughout the range of carriage travel geared with the frame-borne shaft, 55 and means for rotating the shaft borne by the bed plate.

3. In a drilling machine the combination of a bed-plate, a frame pivoted to the bed plate, manually operated means for causing 60 the frame to swing pivotally on the bed plate, a screw extending longitudinally of the frame, a carriage movable longitudinally of said frame and threaded on said screw, manually operated means for turning the 65 screw and effecting carriage movement, a shaft rotatably mounted on the bed plate, a shaft rotatably mounted in the frame and articulated to the first named shaft in a universal joint coaxial with the frame pivot, 70 a drill shaft borne by the carriage and geared with the frame-borne shaft, and means for driving the first named shaft.

In testimony whereof I have hereunto set my hand.

JACOB W. CAMPBELL.
